UNITED STATES PATENT OFFICE.

CHARLES M. MARKHAM, OF CHICAGO, ILLINOIS.

FORM FOR CONCRETE GIRDER CONSTRUCTION.

1,200,124.

Specification of Letters Patent.

Patented Oct. 3, 1916.

Application filed June 30, 1910. Serial No. 569,643.

To all whom it may concern:

Be it known that I, CHARLES M. MARKHAM, a citizen of the United States, residing at Chicago, in the county of Cook and State 5 of Illinois, have invented certain new and useful Improvements in Forms for Concrete Girder Construction, of which the following is a description.

My invention relates to mechanism for 10 controlling the general form and position of the forms for constructing concrete girders and the like.

The object of my invention is to provide 15 a simple, convenient and efficient device of the kind described, capable of accurate adjustment, yet so constructed in all of its parts that the necessarily rough treatment to which it is often subjected will not seriously impair its efficiency or operativeness.

20 To this end my invention consists in the novel construction, arrangement and combination of parts herein shown and described, and more particularly pointed out in the claim.

25 In the accompanying drawings wherein like or similar reference characters indicate like or corresponding parts: Figure 1 is a front elevation of my device partly in section shown in operation. Fig. 2 is a side 30 elevation of the same also partly in section. Fig. 3 is a section taken substantially on line 3—3 of Fig. 1. Fig. 4 is an enlarged section taken substantially on line 4—4 of Fig. 1. Fig. 5 is a section taken substantially on line 5—5 of Fig. 4. Fig. 6 is an enlarged section taken substantially on line 6—6 of Fig. 1. Fig. 7 is a perspective detail of a portion of my device.

In the preferred construction shown in the 40 drawings, my device consists of a rectangular timber of up-right 1 of suitable length to form a support for the operative parts of my device. A cross arm 2 is provided at the upper end of the up-right extending substantially an equal distance at each side thereof, and provided with suitable braces 3—3 or other convenient means for rigidly maintaining the cross arm in a horizontal position.

50 Suitable means are provided for adjustably securing the cross arm to the up-right. As shown a U shaped staple 4' is provided having both of its arms 4—4 threaded and each provided with a nut 5. A collar 6 is formed upon or secured to each arm 4 near the connecting portion between the arms,

and a pair of plates 7 and 8 are provided, each having a suitable opening near its extremities to receive the arms 4—4 and serve as a clamp for securing the cross arm and up-right together. The distance between the arms 4 is sufficient to receive the end of the up-right between them. One of the plates 7 is positioned at the front of the cross arm 2, and the arms 4 extend through the plate 7 and cross arm 2 along each side of the upper end of the up-right and through the plate 8 so that by adjusting the nuts 5 the cross arm 2 will be firmly clamped to the up-right 1. Its position may however be adjusted upon the up-right as desired to accommodate any slight variations in the height of the girder above the base upon which my device is resting.

The braces 3—3 are preferably each rigidly secured to the cross arm 2 near its extremities and extend downward to the up-right 1 where a staple 4², similar to the staple 4' is provided with its arms 4 preferably extending through the end portions 80 of the braces 3 to rigidly and adjustably clamp them to the up-right. The bottom or lower member 9 of the girder form preferably rests directly upon the cross arm 2 and the side members 10—10 of the form are 85 forced against the sides of the bottom member and rigidly held in position by a pair of channel bars 11—11 adjustably connected to, and supported by, the cross arm 2.

Any suitable means may be provided for 90 adjustably attaching the bars 11—11 to the cross arm 2. In the form shown a member 12 is provided, having a hook 14, adapted to slidably engage the cross arm. The bottom portion of the member 12 is tubular and 95 of suitable form to receive the bar 11 and admit of its free longitudinal movement therethrough. Laterally projecting ears or lugs 15 are provided upon the member 12 suitably spaced from each other to receive a bolt 16, which is pivotally attached to the staple 4' between them. In the preferred 100 construction the lugs 15 each have a flat bearing surface for a washer 17 at right angles to the bolt 16 with a projecting rib 18 at the outer edge of each, adapted to engage the straight side of the washer 17 to control its position and prevent its rotation with the nut 19 as shown in Fig. 2. The 110 transverse position of the lower end of the bars 11 may be controlled in any suitable manner. As shown a series of notches

23—23 are provided in the inner flange of the channel bar 11 and a member 22 is provided, having a part adapted to rest against the face and inner flange of the bar 11 with 5 a part 24 suitably formed to engage any of the notches 23 to prevent its longitudinal movement upon the bar 11. A bolt 20 is pivotally attached to the staple 4² with its free end extending through an opening 25 in the 10 part 22 and having a nut 21 adapted to engage the part 22 to force the same outward. A jam nut 26 or other convenient means is preferably provided to lock the nut 21 in its adjusted position. A cotter pin 27 is provided in a suitable transverse opening near the extremity of the bolt 20 so that when the 15 part 22 is disengaged from the bar 11 it will not escape from the bolt.

The vertical position of the bar 11 may be 20 controlled in any suitable manner. In the form shown a part 30 is provided upon the member 12 having a jaw 32 pivotally mounted at its lower end and arranged to freely adjust itself transversely of the part 25 30 and to cramp upon the bar 11 to prevent its downward movement, the parts being so formed that the bar 11 is free to be moved upward as desired, but will be automatically locked against downward movement and 30 held in position by the jaw 32.

In the preferred construction suitable means are provided at the upper end of the bar 11 to engage and support any joists or other floor or ceiling members in their 35 proper position in relation to the girder being formed. In the preferred construction shown a part 35, arranged to coöperate with the upper part of the bar 11 to form a jaw is rigidly attached to the bar 11 by suitable 40 rivets 36 or other convenient means. The portion of the part 35 positioned between the flanges of the bar 11 is preferably beveled laterally so that when the part 35 is in position it will be wedged between the flanges 45 of the bar 11 and accurately and rigidly held in position. Obviously where a girder is employed for supporting a floor or ceiling, it would be inconvenient to provide one of my devices for each of the joists to be 50 supported by the girder. For this purpose a stirrup 40, as shown in Fig. 7 is provided

having one end 41 formed to engage and fit between the flanges of the beam 11 and of suitable width to snugly fit against the part 35 so that when the part 41 is in position it 55 securely interlocks with the jaw at the upper end of the beam 11 and prevents lateral displacement of the stirrup. The lower end of the part 40 is provided with a hook 42 adapted to engage a beam or timber 43 to 60 support the same in position, the depth of the beam preferably corresponding to the length of the part 40, so that the top surface of the beam will accurately correspond with the top surface of the part 41 and the 65 several joists resting upon the beam 43 will be accurately alined horizontally. When in operation the several parts are suitably positioned upon the up-right and brought to the proper level to support the bottom member of the form, the bars 11 are then adjusted to the proper elevation to support the joists and adjusted transversely to support the side members 10—10 of the form, which may then be filled in the usual or any 70 75 preferred manner.

Having thus described my invention it is obvious that various immaterial modifications may be made in my device without departing from the spirit of my invention, 80 hence I do not wish to be understood as limiting myself to the exact form or construction shown.

What I claim as new and desire to secure by Letters Patent is:

In a device of the kind described, a channel bar provided with a jaw at its upper end adapted to loosely engage a horizontal beam to support the same in position, in combination with a part adapted to engage 90 said jaw and interlock therewith to prevent lateral disengagement, said part being adapted to support a second beam in fixed relation to said first beam.

In testimony whereof, I have hereunto signed my name in the presence of two subscribing witnesses.

CHARLES M. MARKHAM.
